VICTOR YORK, OF LOS ANGELES, CALIFORNIA.

LONG-STROKE PUMPING APPARATUS.

Application filed November 11, 1924. Serial No. 749,133.

This invention relates to deep well pumping equipment, and relates particularly to a design of equipment of this sort which is suitable for oil well use.

In the oil well industry oil is pumped from a well by means of pumping equipment which generally includes a pump barrel in which a pump plunger is reciprocable. The barrel of the pump is attached to the lower end of a string of drill tubing, through which tubing oil is pumped to the surface of the well when the plunger is reciprocated within the barrel. A string of sucker rods attaches to the pump plunger and extends to the surface of the well, where it is connected with reciprocating means. The present reciprocating means includes a walking beam which is swingably pivoted on a Samson post and which is reciprocated by means of a walking beam crank. The travel of the end of the walking beam to which the string of sucker rods is connected does not exceed four feet in most cases. In fairly deep wells equipped with the present pumping equipment the pump stroke is considerably less than the stroke of the pump operating mechanism at the well surface; the chief reason for this being due to the elasticity of the sucker rod string. The load of oil placed on the plunger of a pump during its upward stroke in a well of 2000 to 3000 feet in depth is enormous, and owing to the elasticity of the material from which the sucker rods are formed, all of the motion of the walking beam will not be transferred to the pump plunger.

To explain this condition more clearly, let us assume the following hypothesis:

Disregarding all other causes of deficiencies in a pump, let us consider that the stroke of the walking beam is four feet and that the stretch in the string of sucker rods, due to the elasticity of these rods, is two feet. It will be seen that under these circumstances, the movement of the pump plunger would be two feet. One-half of the motion of the sucker rod string then would be lost due to stretching, and the travel of the plunger relative to the walking beam would be one-half as much, and, consequently, the output of the pump would be 50 per cent less. It should be understood that the stretch in the sucker rods occurs during the

upward stroke, due to the enormous load placed thereon at this time, and that the rods return to normal position on the downward or return stroke of the pump.

It is an object of this invention to provide deep well pumping equipment in which the loss of efficiency, due to elasticity in the string of sucker rods, is greatly reduced. My invention comprises a pump construction which employs an extra long pumping barrel and mechanism for giving the plunger of the pump an extra long stroke. To illustrate the manner in which this will overcome or reduce the loss of efficiency in a pump of this character, let us assume that the stroke of the pump is eight feet in place of the stroke of the usual pumping equipment which is four feet. The elasticity in the sucker rod string being two feet, it will not cause as great a loss of output as is present in the old types of pumps. The stretch in the first illustration was one-half that of the entire stroke of the pump, whereas the stretch in my equipment is only one-quarter of the stroke of the plunger; therefore, the loss due to elasticity is only 25 per cent, whereas in the other pump it was 50 per cent. It is evident from this that a pump having a stroke of eight feet, as in my invention, reduces this loss of output 50 per cent over that of the pump having a four foot stroke.

It is another object of this invention to provide a pumping construction in which the loss, due to the time taken for the working valve to close, is considerably reduced. To illustrate this point, let us consider that upon the upward stroke of a plunger, the travel is two inches before the closing of the valve. In a pump having a stroke of four feet, as does the present pumps, 1/24th of the stroke is lost. In the equipment of my invention, the stroke being eight feet, the loss is reduced 50 per cent; in other words, the time taken for the standing valve to close is only 1/48th of the stroke of the pump.

It is a further object of the invention to provide pumping construction in which the life of the polish rod will be lengthened, due to its not being flexed by the reciprocating mechanism. In pumping equipment the upper end of the string of sucker rods

is called a "polish rod", this rod extending through a stuffing box situated at the upper end of the pump tubing. The walking beam to which the polish rod is attached being pivotally swung, swings the upper end of the polish rod as it is reciprocated. The end of the walking beam follows an arcuated path, due to the fact that it pivots around the central part thereof.

10 The pumping construction of my invention comprises a flexible member which attaches to the sucker rod and which extends directly upward therefrom. A movement of the flexible member is arranged to reciprocate the polish rod, the pull being exerted on the polish rod in direct alignment with the extension thereof, and absolutely no bending in the polish rod is present.

It is a still further object of my invention to provide a pumping equipment which may utilize a number of the usual attachments employed during the drilling of the well and which requires the supplying of only a few extra parts. In this manner I 25 am able to provide pumping mechanism in which the investment is comparatively low.

Other objects and advantages of my invention will be made evident hereinafter.

Referring to the drawings which are for 30 illustrative purposes only,

Fig. 1 is a sectional view illustrating the utility of my invention, this view being essentially diagrammatic.

Fig. 2 is a view looking downwardly on 35 the floor of a derrick employing pumping equipment of my invention.

Fig. 3 is an enlarged view clearly illustrating the mechanism employed in my apparatus and supplying a motion to the polish rod.

Fig. 4 is a section taken as indicated by the line 4—4 of Fig. 3.

As shown in the drawings, 11 designates a well having a pump tube 12 extended 45 thereinto which has a pump 13 situated at the lower end thereof. This pump 13 includes a pump barrel 14 and a pump plunger 15. The barrel 14, as is clearly evident from the drawing, is much longer than the usual length of a pump barrel for a plunger of the size shown. Attached to the upper end of the plunger 15 and extending upwardly through the tubing 12 is a string 50 of sucker rods 16 having a polish rod 17 attached to the upper end thereof. This polish rod 17 extends through a stuffing box 20 secured on the extending end of the pump tubing 12. The casing 21 of the well 55 11 is provided with a casing head 22, through which the well tubing 12 extends, and from which there extends a pipe line 23 for conducting gas from the well. A reciprocation of the polish rod 17 serves to 60 reciprocate the pump plunger 15 in the barrel 14 in a manner to elevate oil through

the tubing 12. As the oil is pumped, it passes upwardly through the tubing 12 and is conducted therefrom through a pipe 25, which extends to a suitable storage (not shown).

70 The mechanism provided by my invention for reciprocating the plunger 15 includes a pair of slide members 30 which, as clearly shown in Fig. 4, may be in the form of I-beams which are bolted to the floor 31 of the derrick 32 of the well, these slides 30 being positioned so that the inner ends thereof extend adjacent and slightly to one side of the well, as is clearly shown in Fig. 2. A stationary wheel 34, rotatable on a shaft 35, is 75 secured at the inner ends of the slides 30 by means of brackets 36, which are bolted on the slides 30 by means of suitable bolts 37. The wheel is placed on the shaft 35 between the brackets 36 so as to be situated centrally 80 with regard to the slides 30. At the outer end of the slide members 30 is a movable wheel 40, this wheel 40 being rotatable on a shaft 41 which is supported by travelling blocks 42. The blocks 42 are of a construction, as clearly shown in Fig. 4, providing T slots 44 on the lower portion of the base thereof, these T slots 44 being provided by inwardly projecting lips 45. The upper flanges 47 of the slide members 30 are arranged 85 to extend into the T slots 44 when the blocks 42 are in place, as is shown in the drawing.

90 Adjacent to the stationary wheel 34 and slightly to the outside thereof is a bar 50 which is secured on the upper faces of the slides 30 by bolts 51. A flexible member in the form of a cable 53 is attached to the bar as by the extension of the end thereof through an opening 55 in the bar 50, and by 95 the employment of a cable clamp 56. The cable 53 extends outward over and around the movable wheel 40, and inward under and around the stationary wheel 34. The cable 53 is then extended upward and over a guide 100 sheave 58.

105 In the drawings I have shown the guide sheave 58 as being one of the sheaves of a crown block 59 which is situated at the top 110 of the derrick and which is employed during the drilling of the well. In this manner I am able to utilize this portion of the present equipment of the well. It will be understood, however, that if desired, other guiding means could be employed equally as well. It is important, however, that the guide sheave 58, whether it be a portion of the crown block 59 or whether it be an extra supply part, be situated in such position that the inner point of the periphery be located 115 precisely above the center of the well or in alignment with the extension of the polish rod 17. The cable 53 extends upward from the stationary wheel 34, over the guide sheave 58, as shown in Fig. 1, and from 120 125 130

thence extends downward and is attached at 62 to the upper end of the polish rod 17. The movable wheel 40 is arranged to be reciprocated from the position shown in full lines in Fig. 1 into the position indicated by the dotted lines 64 in this figure, the sliding blocks 42, travelling as is evident along the upper flanges 47 of the slide I-beams 30. Means for reciprocating the movable wheel 40 is provided in the form of a crank 65, from which there extends a connector 66. The crank 65, in order to reduce additional parts, may be the usual walking beam crank of the derrick equipment, this crank being secured on a shaft 67 which takes the band wheel construction 68, said shaft being supported in bearings 69 supported by a structure 70. The connector 66 may be of a rigid or flexible nature, this being made more clear 20 later on. In this modification, I have intended that the connector 66 be made from a flexible cable. The end of the connector 66, opposite from the crank 65, is secured to the travelling blocks 42 by means of a yoke 72, this yoke having a clamp 73 by which the connector 66 secures thereto, and being attached to the travelling blocks 42 by suitable bolts 75.

The operation of the equipment just described is substantially as follows:

It will be understood that there is at all times the weight of the string of sucker rods and the pump plunger 15 upon the live end 77 of the cable 53. This creates a pull upon the cable 53, which tends to move the movable wheel 40 toward the stationary wheel 34, as will clearly be seen from the drawings. From this it is clear that the purpose of the crank 65 is not to reciprocate the movable wheel 40 into both positions, but that chiefly it is for the purpose of moving this movable wheel 40 from the position indicated by the dotted lines 64 into the position indicated by the full lines in this figure, the weight of the sucker rods 16 and the plunger 15 being sufficient to move the movable wheel 40 into the dotted position 64. From this it is evident that it is not necessary for the connector 66 to be rigid, owing to the fact that a pull 40 or tension is the only force exerted thereupon. When the crank 65 is reciprocated, one-half the revolution thereof serves to move the movable wheel 40 from the position 64 into its outer position, and during the other half of the revolution the movable wheel is returned to the position 64 due to the weight of the pump plunger and the string of sucker rods thereupon. During the return stroke, the crank and connector 66 serve 50 merely to control the speed at which the wheel will return to the position 64.

The principle employed for moving the live end 77 of the cable 53 is substantially the reverse that of block and tackle; in other words, instead of pulling upon the live end

77 to move the movable wheel 40, I reciprocate the movable wheel 40 to supply motion to the live end 77. In this illustration I have employed two wheels in the construction. Consequently, the movement in 50 the live end 77 of the cable 53 is twice the travel of the movable wheel 40, this complying with the block and tackle principle, as it is seen that the movement of the block and tackle rope moves the movable 75 pulley thereof in proportion to the number of sheaves employed therein. Although I have only shown two wheels, it should be clearly understood that I may employ any number of wheels I desire. Considering 80 that the travel of the movable wheel 40 is four feet, the movement of the live end 77 of the cable 53 will be eight feet. This movement being transferred through the string of sucker rods 16 to the pump 85 plunger 15, causes the plunger to have a travel of eight feet, which is double that of the usual pumping plunger.

From the foregoing description it is clearly evident that the construction of my 90 invention employs various equipments of the derrick, which is a standard part thereof used in the drilling of the well. The additional parts which must be supplied are few and, therefore, the investment will be 95 less than that of other pumping constructions. The life of the polish rod of the pump will be greatly prolonged due to the fact that no bending is incurred therein by pumping equipment, as the pull exerted on 100 the polish rod 17 is in direct alignment with the extension thereof. The novel pumping construction shown by my invention gives a stroke to the plunger which is substantially double that of the present type of pumping 105 construction, and it serves to effectively increase the output substantially 50 per cent as mentioned in the preamble of this specification.

I claim as my invention:

1. In combination: a pump barrel; a pump plunger; a cable associated with said plunger; a stationary wheel over which said cable extends; a movable wheel over which said cable extends, said movable wheel 115 being slidably mounted upon a base; and means for moving said movable wheel so as to move said cable in a manner to reciprocate said plunger.

2. In combination: a pump barrel; a pump plunger; a string of sucker rods connected with said plunger; a cable attached to said string of sucker rods; a sheave over which said cable extends, said sheave being situated in such a manner that said cable 120 will extend from said string of sucker rods in axial alignment therewith; a stationary wheel over which said cable extends; a movable wheel over which said cable extends, said movable wheel being slidably mounted 125 130

upon a base; and means for moving said movable wheel so as to move said cable in a manner to reciprocate said plunger.

3. In combination; a reciprocating pump comprising a barrel and plunger; a cable associated with said plunger for moving said plunger; means for moving said cable so as to move said plunger, said means comprising a stationary wheel and a movable

wheel over both of which said cable extends, ¹⁰ said movable wheel being slidably associated with a pair of horizontal tracks; and means for moving said movable wheel on said tracks.

In testimony whereof, I have hereunto ¹⁵ set my hand at Los Angeles, California, this 3rd day of November, 1924.

VICTOR YORK.
